No. 683,774.

Patented Oct. 1, 1901.

W. D. KILBOURN.
BANDAGE ROLLING MACHINE.

(Application filed Jan. 21, 1901.)

(No Model.)

UNITED STATES PATENT OFFICE.

WILLIAM DOUGLAS KILBOURN, OF PUEBLO, COLORADO, ASSIGNOR OF
ONE-HALF TO CHARLES O. RICE, OF SAME PLACE.

BANDAGE-ROLLING MACHINE.

SPECIFICATION forming part of Letters Patent No. 683,774, dated October 1, 1901.

Application filed January 21, 1901. Serial No. 44,097. (No model.)

To all whom it may concern:

Be it known that I, WILLIAM DOUGLAS KILBOURN, a citizen of the United States, and a resident of Pueblo, in the county of Pueblo 5 and State of Colorado, have invented a new and Improved Bandage-Rolling Device, of which the following is a full, clear, and exact description.

This invention relates to improvements in 10 devices for forming bandages or other strips of material into rolls.

In devices heretofore made for rolling bandages it is necessary to remove the adjustable head in order to rove the bandage between the guide-bars.

It is the object of my present invention to so arrange or mount the guide-bars that the material may be readily placed between them without removing the adjustable head.

20 I will describe a bandage-rolling device embodying my invention and then point out the novel features in the appended claims.

Reference is to be had to the accompanying drawings, forming a part of this specification, 25 in which similar characters of reference indicate corresponding parts in all the figures.

Figure 1 is an end view of a rolling device embodying my invention. Fig. 2 is a front view thereof. Fig. 3 is an end view opposite 30 that of Fig. 1 and partly in section, and Fig. 4 is a section on the line 4-4 of Fig. 2.

Referring to the drawings, 5 designates a fixed head attached to an arm 6, designed to be clamped to a table or other support. Extended from the arm 6, below the head 5, is a 35 rod 7, and adjustable longitudinally of this rod is a movable head 8. A winding-shaft 9 has its bearings in these two heads 5 and 8, and obviously by moving the head 8 toward 40 or from the head 5 the proper length of shaft may be provided for the width of the material to be wound.

Extended from the arm 6 is a fixed guide-bar 10. This bar 10 passes loosely through 45 an opening in an arm 11, extended from the adjustable head 8, and the said head 8 may be secured in position as adjusted on this bar 10 and the arm 11 by means of a set-screw 12.

50 Mounted to swing at the opposite sides or above and below the fixed bar 10 are the

guide-bars 13 and 14. The bars 13 and 14 are connected at one end and extended through openings in the arm 6, as clearly indicated in Fig. 1, and are mounted to swing on a pivot 55 15, attached to lugs 16 on the outer side of said arm. A spring 17 is connected at one end to the bars 13 and 14 and at the other end to the arm. The arm 11 is provided with depressions or recesses to receive the free 60 ends of said bars 13 and 14, and they may be held within these depressions by means of a hook-bolt 18, mounted to slide in an opening in said arm 11 and having its hook end adapted to engage over the top of the upper 65 bar 14. A spring 19 normally holds or moves this locking-bolt to its locking position.

In operation when it is desired to roll a strip of material the locking-bolt 18 is to be pressed upward to release the bars 13 and 70 14, so that the spring 17 will swing said bars upward or outward relatively to the middle bar 10. Then the material is to be placed over this middle bar 10 and connected at one end with the winding-shaft. After this the 75 bars 13 and 14 are to be moved to their closed position, and in this movement the bar 14 by engaging the curved upper edge of the hook on the locking-bolt will move said bolt until the said bar moves underneath the 80 same, when the spring 19 will return the bolt to its locking position, and obviously it is not necessary while placing the strip to change the adjustment of or to remove the head 8. While I have shown two outer bars 85 13 and 14 as mounted to swing relatively to the center bar 10, it is obvious that the center bar may be mounted to swing relatively to the outer bars without departing from the spirit of my invention. In such event, however, the strip of material would pass over the uppersides of the outer bars and over the outer side of the center bar instead of as shown in Fig. 4.

Having thus described my invention, I 95 claim as new and desire to secure by Letters Patent—

1. In a device for winding strips of material, a shaft, a fixed head, a head adjustable on the shaft, arms extended from the heads, 100 one of said arms having openings and the other having notches, a guide-bar having

fixed connection with the arms, side guide-bars extended through the openings of the arm and adapted to engage in the notches of the other arm, said side guide-bars being pivoted at the outer side of the arm having openings and connected together at the pivoted end, and means for locking the side guides in closed position, substantially as specified.

10 2. A bandage-rolling device, comprising an arm, a fixed head on said arm, a rod extended from said arm, a guide-bar extended from said arm, a head having sliding connection with said rod and bar, guide-bars at the opposite sides of the fixed bar and mounted to

swing, the said last-named bars being connected together at their pivoted ends, a spring for moving said swinging bars to their open position, and a sliding locking-bolt and movable with the sliding head for securing said 20 swinging bars in their closed position, substantially as specified.

In testimony whereof I have signed my name to this specification in the presence of two subscribing witnesses.

WILLIAM DOUGLAS KILBOURN.
